W. E. G. ROBINSON & J. P. TOOMEY.
LIFTING ROD AND BUSHING FOR RING SPINNING FRAMES.
APPLICATION FILED JUNE 9, 1917.

1,263,934.

Patented Apr. 23, 1918.

UNITED STATES PATENT OFFICE.

WILLIAM E. G. ROBINSON AND JAMES P. TOOMEY, OF CHARLOTTE, NORTH CAROLINA.

LIFTING-ROD AND BUSHING FOR RING-SPINNING FRAMES.

1,263,934.

Specification of Letters Patent. Patented Apr. 23, 1918.

Application filed June 9, 1917. Serial No. 173,874.

To all whom it may concern:

Be it known that we, WILLIAM E. G. ROBINSON and JAMES P. TOOMEY, citizens of the United States, residing at Charlotte, in the county of Mecklenburg, State of North Carolina, have invented certain new and useful Improvements in Lifting-Rods and Bushings for Ring-Spinning Frames, of which the following is a description, reference being had to the accompanying drawing and to the figures of reference marked thereon.

The invention relates to improvements in lifting rods and bolsters for use on ring-spinning frames and twisters.

The objects of the invention are to so construct the lifting rod and its bolster that friction between them will be materially lessened, sticking of the rod in the bolster prevented and free passage of lint through the bolster permitted.

These objects are accomplished by the construction shown in the accompanying drawing in which—

Figure 1 is a sectional elevation of a portion of a ring-spinning frame with our improved lifting-rod and bushing applied.

Fig. 2 is a side elevation of the lifting-rod and its bushing.

Fig. 3 is a perspective of the same, and Fig. 4 is a section on the line 4—4, of Fig. 2.

1 designates the ring-rail; 2 the bolster-rail; 3, the lifter-rod and 4 the spindle carrying the bobbin 5.

The lifter-rod 3, is formed with a plurality of parallel longitudinal bearing edges 6, instead of being formed round as usual and in the specific form illustrated these edges 6, are produced by forming the rod 3 triangular in cross section.

7, designates the lifter-rod bushing the bore of which is formed many sided as indicated at 8; the bore being triangular in the specific form shown.

The bore of the bushing 7 is larger than the diameter of the rod 3, and the edges 6 of the rod engage the three flat walls 8 of the bushing 7, as shown in Fig. 4, so that three clearance openings are formed for the free passage of lint therethrough. The spindle 3 has a plurality of very narrow bearing edges 6, as before stated, which greatly reduces the friction between the spindle and its bushing and also prevent sticking of the lifter-rod in the bushing which occurs where the engaging surfaces of the rod and bushing are

round and close fitting. To prevent any turning or twisting of the lifter-rod 3, in its bushing 7, the longitudinal working edges 6 of the rod are flat instead of sharp; that is 60 the apices of the triangles will be truncated or flattened and will be about an eighth of an inch wide where they engage the flat faces 8 of the bushing 7.

The invention is not restricted to the particular form of polygonal engaging surfaces between the lifting rod and the bore of the bushing so long as the friction reducing means and lint clearance openings are produced and rotation of the rod in the bush- 70 ing is prevented.

The term polygonal as used in the claims is therefore to be given the broadest interpretation.

Having thus described the invention, what 75 is claimed as new is:—

1. The combination with a lifter-rod, of a bearing therefor having a bore receiving the rod, there being engaging surfaces formed at intervals between the rod and 80 the bore and opposed clearance spaces between said engaging surfaces.

2. The combination with a lifter-rod having a plurality of parallel bearing edges and non-engaging surfaces therebetween, of 85 a bearing having a bore engaged by said bearing edges and provided with clearance spaces opposed to the non-engaging surfaces of the lifter-rod.

3. The combination with a lifter-rod po- 90 lygonal in cross section to form longitudinal bearing edges and intervening non-engaging surfaces, of a bearing having a polygonal bore, the flat walls of which are engaged by said longitudinal bearing edges and the in- 95 tervening angular clearance spaces being opposed to the corresponding non-engaging surfaces, formed on the lifter-rod.

4. The combination with a bushing adapt- ed to be inserted in the usual bolster rail 100 opening and provided with a supporting shoulder to engage the upper side of said rail, of a lifter-rod working in said bushing, engaging surfaces being formed at intervals between the rod and the bore of the bushing; 105 clearance spaces being formed between said engaging surfaces within the bushing.

5. The combination with a lifting rod polygonal in cross section, of a bushing hav- ing its bore polygonal in cross section; the 110 parallel working edges of the rod, engaging the flat walls of the bore intermediate of the

angles thereof; whereby clearance spaces for lint are provided by the opposed non-engaging surfaces of both the rod and bushing bore.

5 6. The combination with a lifting rod triangular in cross section and having its angles flattened, of a bushing having a triangular bore; the flattened working edges of the rod engaging the flat walls of the bush-
10 ing between the angles thereof; whereby ro-

tation of the rod is prevented and clearance spaces for lint are provided.

In testimony whereof we affix our signatures in the presence of two witnesses.

WILLIAM E. G. ROBINSON.
JAMES P. TOOMEY.

Witnesses:

J. C. CROWELL,
T. J. PAYNE.
